UNITED STATES PATENT OFFICE.

FRANK M. McDERMOTT, OF TROY, NEW YORK.

COLLAR BUTTON.

Application filed October 28, 1921. Serial No. 511,026.

To all whom it may concern:

Be it known that I, FRANK M. McDERMOTT, a citizen of the United States, residing at Troy, in the county of Rensselaer 5 and State of New York, have invented certain new and useful Improvements in Collar Buttons, of which the following is a specification.

This invention relates to collar buttons 10 and has for its object the production of a collar button, which may be conveniently attached to a collar band of a shirt, after the button has been attached to the collar.

Another object of the invention is the 15 production of simple collar button, which may be cheaply manufactured.

Other objects and advantages of the present invention will appear throughout the following specification and claims.

20 In the drawings:

Figure 1 is a vertical section through a shirt band, showing the collar button in place.

Figure 2 is a rear elevation of the shirt 25 band or collar band, the button shank being shown in transverse section.

Figure 3 is a longitudinal section through the collar band of a shirt, the button being shown in top plan.

30 Figure 4 is a perspective view of the collar button.

By referring to the drawings it will be seen that 1 designates the fan-shaped body of the collar button, which is flared outwardly from the bottom toward the top thereof, and constitutes a substantially flat plate. The lower end of the body is provided with an upwardly bent neck 2, terminating in an outwardly extending shank 3, this shank 3, supporting a plurality of 35 pivotally mounted levers 4 of the usual type.

In operating the button, the levers 4 are passed through the button hole of a collar before the same is placed on the wearer.

45 The fan-shaped body is then placed under the guard of the neck band as shown in Fig-

ures 1 and 2. The mounting of the collar button in engagement with the collar band as described will permit the same to move slightly to the right or left while the front 50 ends of the collar are being fastened to the front of the collar band. For instance, while one end of the collar is being fastened to the collar band, the rear collar button may easily slide in that direction, and when the 55 opposite end of the collar is being fastened, the rear collar button may easily slide in the corresponding direction.

It should be understood that certain detail changes in design, etc., may be made 60 without departing from the spirit of the invention, so long as these changes fall within the scope of the appended claims.

What is claimed is:

1. A collar button of the class described 65 comprising a plate, a neck bent in a substantially parallel relation to the plate, said neck terminating in a laterally extending shank adapted to extend through the button-hole of a collar, and a member carried by 70 the outer end of the shank for reception between the plies of a collar.

2. A collar button of the class described comprising a fan shaped plate tapering toward the bottom thereof, and terminating in 75 an upwardly extending neck bent in a substantially parallel relation to the plate, said neck adapted to pass under and around the lower edge of the outer ply of the ordinary collar band, said neck terminating 80 in a laterally extending shank adapted to extend through the button hole of a collar, and a member pivotally secured to the outer end of the shank to guard the collar button against displacement when in use. 85

In testimony whereof he affixes his signature in presence of two witnesses.

FRANK M. McDERMOTT.
